UNITED STATES PATENT OFFICE.

HENRY W. NAGEL, OF CHICAGO, ILLINOIS, ASSIGNOR TO THOMAS H. FERGUSON, OF OAK PARK, ILLINOIS.

REVERSING MECHANISM FOR HOISTS.

Application filed July 21, 1921. Serial No. 486,483.

The present invention relates to reversing mechanisms for hoists of the type in which a hoisting drum is advanced and returned through a given rotational distance in response to automatic control. Such hoists are commonly employed to raise and lower buckets in conveying systems for handling coal and the like.

One object of the invention is to provide a novel association of parts for bringing about the reversals in the rotation of the drum. To this end I employ a main gear train for driving the drum in one direction, a reversing gear train for driving the gear in the opposite direction, clutches for alternately throwing these gear trains into service, and an oscillating constantly running reversing gear. The latter per se constitutes the subject matter of my application Serial No. 474,667, filed June 3, 1921.

Another object of the invention is to provide means for preventing the return of the drum when moving in the hoisting direction. This is to prevent dropping the load by reason of the failure of some part of the mechanism to function properly. In its preferred embodiment this means is in the form of a ratchet mechanism under the control of said reversing gear. As the load is being hoisted, a pawl engages the teeth of a ratchet wheel and as the drum is being returned the pawl is held free of the wheel.

I also present herewith the disclosure of novel braking means and a new adjustment of brake members but the same are not claimed herein but are reserved for a divisional application. Their disclosure, however, seems desirable in order to enable the present invention to be completely understood.

Other objects of my invention are to produce a hoist mechanism of economical and effective construction, and one which may be readily inspected and repaired.

The several features of the invention will be best understood upon reference to the following detailed description taken in connection with the accompanying drawings, and the scope of the invention will be particularly pointed out in the appended claims.

In said drawings, Fig. 1 is a plan view of a hoist having reversing mechanism con-

structed in accordance with the present invention. Fig. 2 is a side elevation of the same, parts being broken away for clearance and compactness of the figure. Fig. 3 is a horizontal section taken on a plane indicated by the line 3—3 of Fig. 2. Fig. 4 is a substantially vertical section taken on a plane indicated by the line 4—4 of Fig. 2, parts being broken away for clearance. Fig. 5 is a detail view of a portion of the means for controlling the ratchet mechanism by which the drum is prevented from reversing when operating in a hoisting direction. Fig. 6 is a perspective view of the inner ring of one of the emergency brake members. Fig. 7 is a similar view of the outer ring of the same brake member, and Fig. 8 is a similar view of the reciprocating frame of the reversing gear. Throughout these views like characters refer to like parts.

Referring to said drawings in detail, 10 designates the frames upon which the various parts of the hoist are mounted. There are two such frames which are spaced apart and, as clearly illustrated, are irregularly shaped so as to provide bearings for the different shafts. Each frame 10 is provided with a triangular portion having inclined flanges 11 and 12 and vertical flanges 13, together with intervening webs 14 and 15. This portion of each frame 10 forms a pedestal for a bearing 16 for the drum shaft 17. In the present instance, the bearing 16 comprises a lower box or pedestal in which the journal of the shaft rests, and an upper box or pedestal cover which is suitably secured to the lower box or pedestal by bolts 18. Obviously, any desired bearing construction may be employed for this shaft. The drum 19 is mounted upon the shaft 17 at a point intermediate of its length. This drum preferably comprises an annular shell 20 and ends 21 and 22 which are provided with sleeves 23 and 24, which are, in turn, secured to the shaft 17 by a key 25. At this point it may also be noted that the end 22 is provided with a conical brake member 26, which constitutes one of the members of the emergency brake previously referred to. As clearly illustrated, the ends 21 and 22 extend beyond the shell 20 so as to provide a space for the cable which is to be

wound upon the drum. Obviously, the shell 20 may be spirally grooved so as to provide for the regular and orderly winding of the cable upon it. This, however, is a detail 5 which may be left to the designer, and I have, therefore, not taken occasion to illustrate it. The shell 20 and ends 21 and 22 may be secured together in any desired way, as by welding.

10 The drum shaft 17 also has keyed to it a gear wheel 27 which is adapted to be driven by a meshing pinion 28 mounted upon an intermediate shaft 29 which, in turn, is provided with a gear wheel 30. The shaft 29 is journaled in bearings 31 upon horizontal portions of the frames 10. Adjacent to these bearings, each frame is provided with horizontal flanges 32, vertical flanges 33, and an intervening web 34. The gear wheel 30, in turn, meshes with a pinion 35 loosely mounted on the driving shaft 36. The same gear wheel also meshes with a pinion 37 keyed to the reversing shaft 38. These shafts 36 and 38 are suitably journaled in 25 bearings upon the frames 10, as clearly illustrated. The reversing shaft 38 also has keyed to it a gear wheel 39 which, in turn, meshes with a pinion 40, loosely mounted upon the driving shaft 36. Thus, we see 30 that there is a main gear train which extends from the driving shaft 36 to the drum shaft 17, and includes the gear wheels 35, 30, 28 and 27. Similarly, there is a reversing gear train, which includes gear wheels 40, 39 and 35. 35 When the former is in operation the drum is rotated in the direction indicated by the arrow in Fig. 2, which is the hoisting direction. When the latter is in service the drum is rotated in the opposite direction.

40 In order to bring these gear trains into service, it is necessary to provide means for connecting pinions 35 and 40 to the shaft 36. For this purpose I provide the pinion 35 with clutch teeth 41, and the pinion 40 with 45 clutch teeth 42. The teeth 41 co-operate with similar teeth 43 upon a sleeve 44 secured for longitudinal movement upon the shaft 36 by a spline or feather 45. The opposite end of the sleeve 44 is provided with 50 clutch teeth 46 which are adapted to co-operate with the clutch teeth 42. With this construction it will be seen that when the sleeve is in the position illustrated in Fig. 4, the pinion 35 is mechanically secured to the driving shaft 36 and the drum is being 55 rotated in its hoisting direction. On the other hand, when the sleeve 44 is moved to its left hand position, as viewed in Figure 4, the pinion 35 will no longer be connected 60 to the driving shaft 36, but pinion 40 will be so connected and the drum will be rotated in the opposite direction.

For the purpose of bringing about these reciprocations of the sleeve 44, I provide the

reversing gear 47 which, as previously noted, 65 in itself, constitutes the subject matter of my application Serial No. 474,667, filed June 3, 1921. This reversing gear includes a frame 48 which is adapted to be constantly reciprocated while the driving shaft is in 70 operation. This frame is shown in detail in Fig. 8, and comprises lateral arms 49, 50, 51 and 52, each of which is apertured at its outer end. The auxiliary or worm shaft 53 passes through the apertures in the arms 49 75 and 50, and the intermediate shaft 29 passes through the apertures in the arms 51 and 52. The frame is thus free to slide along back and forth upon these shafts. This frame 48 carries a depending yoke 54 which embraces the clutch sleeve 44, and co-operates with the collars or projections 55 and 56 upon the sleeve in reciprocating it. The frame 48 is provided with an upper toothed rack 57 and a lower toothed rack 58. These racks co-operate with a gear segment 59 in bringing about reciprocations of the frame. The gear segment 59 is mounted upon a shaft 60 which is provided at its forward end with a bearing 61 mounted upon a transverse 80 channel iron 62 which extends between the frames 10. The rear bearing 63 for the shaft 60 is provided with a transverse frame made up of the inclined members 64 and 65, which connect at their lower ends with the two 85 frames 10 and are brought together at their upper ends to form a support for the bearing 63. The forward end of the shaft 61 is provided with a worm gear wheel 66 which meshes with a worm 67 mounted upon the 90 worm shaft 53. The latter is driven through a pinion 68 secured to the driving shaft 36 and a gear wheel 69 secured to the worm shaft 53. By this construction the shaft 60 is driven contemporaneously with the driving shaft 36. Consequently, the gear segment 59 is constantly rotating while the hoist is operating. This results in repeated 95 reciprocations of the frame 48. When the parts are in the position illustrated in Figure 4, as previously noted, the pinion 35 is clutched to the driving shaft 36 and the drum is being rotated in the hoisting direction. As there illustrated, the frame 48 is at the beginning of its leftward movement. 10 The first tooth in the segmentary gear 59 is just engaging the abutment 70 and, by so doing, starts the frame leftward. The subsequent engagement of the teeth of the segment 59 with the teeth of the rack 57 continues this leftward movement. When the teeth of the segment have passed out of engagement with the teeth of the rack, the frame will have reached its extreme left hand position. Continued rotation of the segmental gear 59 will, by engaging the abutment 71 and the teeth of the lower rack 11 58, cause the frame to move back to the right 12

hand position illustrated. As the frame moves from the position of Fig. 4 the yoke 54 will move out of engagement with projection 56, and after traversing the space between the projections 55 and 56 will engage projection 55 and move the sleeve 44 to the left. In doing so it will first disengage clutch teeth 41 and 43 and thereby disconnect pinion 35 and discontinue the hoisting movement of the drum. As the yoke 54 moves still further to the left, it will carry the sleeve 44 with it and finally bring the clutch teeth 42 and 46 into engagement, thereby clutching the pinion 40 to the driving shaft 36 and causing the drum to rotate in the reverse direction. Again, as the frame 48 starts in its movement to the right, its yoke 54 will disengage projection 55 and finally engage projection 56 and begin to move the sleeve 44 to the right. In doing so, it will first unclutch pinion 40 and stop the reverse rotation of the drum, and then it will clutch pinion 35 to the driving shaft and begin the hoisting rotation of the drum. It will be noted that before and after each hoisting rotation of the drum there is a short interval when the drum is not moving. Where the hoist is used for handling coal in a system such as disclosed by me in my application Serial No. 483,201, filed July 8th, 1921, these intervals allow for the loading and dumping of the receptacle to which the hoisting cable is attached.

Referring now to the mechanism for preventing the drum from reversing its direction of rotation when set to operate in the hoisting direction, it will be noted that I provide upon the intermediate shaft 29 just outward of one of the frames 10, a ratchet wheel 72 which is secured to the shaft. As illustrated more particularly in Figure 2, this wheel 72 co-operates with a lever 73 upon which is a pawl or tooth 74. As there illustrated, the teeth of the wheel 72 are provided with radial faces or shoulders, and the tooth 74 is also provided with a like face or shoulder. The other faces of both the teeth of the wheel 72 and the tooth 74 are inclined. By reason of this construction the tooth 74 will slip over the teeth of the wheel whenever the drum is being operated in the hoisting direction, but in case anything should occur which would cause the drum to begin to reverse its direction of rotation, the square face of the tooth 74 would abut against the radial face of one of the teeth of the wheel 72 and stop the drum, and thus prevent injury to the apparatus. It will be noted that the lever 73 which carries the tooth 74 is pivoted at 75 to projections 76, which extend from a portion of the adjacent frame 10.

In order to move the lever 73 out of tooth engaging position, when it becomes necessary to rotate the drum in its reverse direction, I

provide mechanism which is controlled by the reversing gear 47. It will be noted that the frame 48 of this mechanism is provided with a lateral arm 77 which is bent at its forward end so as to come into close proximity to the channel iron 62. This arm cooperates with the sliding member 78 and the bell crank lever 79, shown more particularly in Fig. 5, to bring about the desired result. The member 78 is provided with two longitudinal slots 80 and 81 through which headed pins 82 and 83, respectively, pass into the web of the channel arm 62. The construction is such that the member 78 may be moved to and fro and will be held in any position by the friction of the parts unless pressure is applied to it through the arm 77 of the reciprocating gear. For the latter purpose the member 78 is provided with two projections 84 and 85. It will be seen that, viewing the parts as shown in Figure 5, when the member 77 presses against the projection 84, the bell crank lever will occupy the full line position and the ratchet lever 73 will be in tooth engaging position. The parts will remain in this position until the member 77 has passed out of engagement with projection 84 and come into engagement with projection 85 and applied pressure enough to force the member 78 toward the right to the dotted line position. When this point is reached the bell crank lever 79 will have its own arm raised and the ratchet lever 73 will occupy the dotted line position.

This is the position in which the tooth 74 is held free of the ratchet wheel 72. Thus a lost motion connection is provided between the reciprocating frame 48 and the reciprocating member 78 by which the latter is actuated only when the former is at or near the extremities of its to and fro movements.

In the operation of this ratchet mechanism, it will be clear that the arm 77 and projections 84 and 85 should be so positioned that the lever 73 will be held in tooth engaging position so long as the drum is being rotated in the hoisting direction. Referring to Fig. 4, this should continue so long as pinion 35 is in clutch with the driving shaft 36. Any time after the frame 48 has moved far enough to unclutch teeth 41 and 43, the arm 77 may engage the projection 85 to raise the ratchet lever 73. This condition of the ratchet lever should remain until upon the return movement of the frame 48 the yoke has nearly reached the point of throwing the clutch teeth 41 and 43 into engagement. Before this latter takes place, the arm 77 should engage the projection 84 to allow the ratchet lever 73 to drop into tooth engaging position.

Referring now to another emergency feature, it will be clear that it is desirable to provide some means for braking the drum, in case it overruns the prescribed distance

for which the reverse gear and other parts have been set or designed. To take care of this condition I provide a brake, in association with the drum, in which the brake parts are fed toward and from each other upon a screw thread. Ordinarily, these brake members do not come into braking engagement. In the prescribed to and fro rotations of the drum the screw feed is insufficient to bring the members into contact. However, in case the drum should overrun, then the screw feed would bring the members into engagement. One of these brake members is the conical member 26, previously referred to as forming part of the end 22 of the drum structure. The other co-operating brake member 86 is mounted concentrically with the shaft 17 and comprises an inner ring 87 and an outer ring 88. The former is provided with a thread 89 which co-operates with a thread 90 upon the shaft 17. The ring 87 carries the conical flange which co-operates with the conical face of the brake member 26. It also has a plurality of semi-circular openings or notches 91. In the present instance, four such are shown. These co-operate with a number of similar notches or openings 92 formed on the interior of the outer ring 88. In the present arrangement, there are several notches 92 for each of the notches 91. These are provided for adjustment purposes. Bolts 93, provided with suitable nuts, are used to fasten the inner and outer rings together to make the complete brake member 86. The notches 91 may be set opposite any desired set of notches 92, and the bolts 93 then pass through the resulting openings. When the nuts are applied to the bolts, the parts are firmly secured together. When thus secured, it is necessary to keep the complete structure from rotating. In the present instance, this is accomplished by giving the outer ring 88 a number of flat faces 94, and these co-operate with a horizontal stool 95 which has a vertical portion 96 which is secured to one of the vertical flanges 13 by a plurality of bolts 97, provided with suitable nuts. The flat face 94 lies in close proximity to the face of the stool 95 according to the particular adjustment, and the brake member 86 is prevented from rotation although it is free to move longitudinally of the shaft along the upper face of the stool. It will be seen that with a given adjustment the rotation of the drum in the hoisting direction will cause the brake member 86 to move toward the brake member 26, but, as previously noted, the desired adjustment is such that the two will not come into braking engagement during the normal hoisting movement of the drum. In case, however, some abnormal condition should arise which would cause the drum to rotate further than it should in the hoisting direction, then the brake members 26 and 86 will come into en-

gagement and prevent further rotation of the drum in that direction.

It should be noted that with the specific construction illustrated more particularly in Figs. 5 and 6, I am able to obtain a very nice adjustment of the brake member 86 upon the shaft 17. Thus, with the outer ring 88 alone, I am able to set the brake member 86 at any one of six positions per revolution; that is to say, at any one of six positions measured in sixths of the pitch of the screw 90. Then, by means of the adjustment provided between the inner ring 87 and the outer ring 88, I am able to still further divide one of these sixths into smaller divisions. The number of such divisions will depend upon the number of openings 92. Thus, it will be seen that I am able to obtain a very fine adjustment of the brake member 86 upon the shaft 17.

It will be apparent that the driving shaft 36 may be driven from any suitable source of power, and I have indicated the shaft as having a square end 98 for the purpose of coupling it to such a source.

It may also be noted that the end of the drum shaft 17 adjacent to the thread 90 is considerably reduced in diameter in order to allow the thread to be cut and the brake member to be assembled upon the shaft. Consequently, I provide upon this reduced portion of the shaft a sleeve or bearing 99 and retain the same in position by a collar 100 which is secured to the shaft by any suitable means, as by a transverse pin 101. By this construction the bearings 16 may be made of the same size and the shaft will accurately fit the same.

Furthermore, I may also call attention to the provision of two stop pins 102 for limiting the movement of the brake member 86 outward from the member 26. These pins are in the form of bolts which extend respectively through the webs 14 and 15 of the adjacent frame 10. Each bolt 102 is provided with nuts 103 and 104 which are threaded upon it and adapted to press against the opposite sides of the penetrated flange to hold the bolt firmly in place. The free ends or heads of the bolts 102 extend beyond the inner edge of the adjacent frame 10 and are in position to abut against the brake member 86 to limit its outward movement. By the nuts 103 and 104, the bolts may be adjusted with reference to the frame 10 to vary the outer limiting position of the member 86. By this means the return movement of the drum is limited in case it should unexpectedly overrun in the return direction, due to some failure of the apparatus to otherwise properly function.

In carrying out my invention, it will be apparent that many changes may be made in the details herein disclosed without departing from the spirit and scope of the

invention. I, therefore, aim to cover all such changes by the terms of the appended claims.

What I claim as new and desire to secure by Letters Patent of the United States is:

1. In mechanism of the class described, the combination of a driven member, a horizontal driving shaft, other shafts parallel to said driving shaft, intermeshing gear wheels on said shafts arranged to drive said member forward for one connection and backward for another connection, shiftable clutches on one of said shafts for establishing said connections individually, an auxiliary shaft parallel to and driven by said driving shaft, a clutch-shifting frame having a depending yoke and lateral supporting arms, said yoke operating upon said clutches to establish said connections and said arms bearing upon said auxiliary shaft and one of said other shafts to support and guide said frame as it is reciprocated, and means for reciprocating said frame in response to the revolutions of said auxiliary shaft.

2. In mechanism of the character described, the combination of a driven member rotatable about a horizontal axis, a driving shaft, other shafts, all of said shafts being parallel to said axis, intermeshing gear wheels on said shafts arranged to drive said member forward for one connection and backward for another connection, shiftable clutches on one of said shafts for establishing said connections individually, an auxiliary shaft geared to said driving shaft independently of said intermeshing gear wheels, a reciprocating frame having lateral arms bearing upon certain of said shafts and slidably lengthwise thereof, a yoke depending from said frame and operative to actuate said clutches to alternately provide said connections in response to the reciprocations of said frame, an additional shaft driven from said auxiliary shaft and extending through an opening in said frame, and cooperating means upon said additional shaft and said frame at the point where the former passes through the opening in the latter for causing reciprocations of the frame in response to rotations of the shaft.

3. In mechanism of the character described, the combination of a driven member, a driving shaft, other shafts parallel to said driving shaft, intermeshing gear wheels on said shafts arranged to drive said member forward for one connection and backward for another connection, shiftable clutches on one of said shafts for establishing said connections individually, a worm shaft parallel to said driving shaft, intermeshing gear wheels for driving said worm shaft from said driving shaft, a worm gear wheel mesh-

ing with the worm on said worm shaft, an additional shaft supporting said worm wheel and extending in a plane at right angles to said driving shaft, a clutch shifting member movable lengthwise of said other shafts, and cooperating means on said additional shaft and said clutch shifting member for causing the rotations of the former to oscillate the latter.

4. In mechanism of the class described, the combination of spaced supporting frames, a driven member having a shaft journaled in said frames, a driving shaft and other shafts parallel thereto journaled in said frames, intermeshing gear wheels on said shafts arranged to drive said driven member forward for one connection and backward for another connection, shiftable clutches on said driving shaft for establishing said connections individually, an auxiliary shaft journaled in said frames above and driven by said driving shaft, a clutch-shifting frame having a depending yoke for engaging said clutches to establish said connections, said clutch-shifting frame being movable lengthwise of said shafts, means for reciprocating said clutch-shifting frame directly from said auxiliary shaft, a ratchet wheel on one of said other shafts outward of one of said supporting frames, a cooperating pawl pivoted to the adjacent supporting frame, and means including a member movable in the plane of movement of said clutch-shifting frame and having a lost motion connection with the same for causing the up and down movements of said pawl at the ends respectively of the reciprocations of said clutch-shifting frame.

5. In mechanism of the class described, the combination of spaced supporting frames, a driven member having a shaft journaled in said frames, a driving shaft and other shafts parallel thereto journaled in said frames, intermeshing gear wheels on said shafts arranged to drive said driven member forward for one connection and backward for another connection, shiftable clutches on said driving shaft for establishing said connections individually, an auxiliary shaft journaled in said frames above and driven by said driving shaft, a clutch-shifting frame having a depending yoke for engaging said clutches to establish said connections, said clutch-shifting frame being movable lengthwise of said shafts, means for reciprocating said clutch-shifting frame directly from said auxiliary shaft, a ratchet wheel on one of said other shafts outward of one of said supporting frames, a cooperating pawl pivoted to the adjacent supporting frame, a transverse member extending between said supporting frames adjacent to said auxiliary shaft, a reciprocating member supported by said transverse member and adapted to be actuated by said clutch-

shifting frame, and a lever for actuating said pawl in response to the movements of said reciprocating member, said pawl actuations occurring at the ends of the reciprocations of said clutch-shifting frame.

6. In mechanism of the class described, the combination of spaced supporting frames, a driven member having a shaft journaled in said frames, a driving shaft and other shafts parallel thereto journaled in said frames, intermeshing gear wheels on said shafts arranged to drive said driven member forward for one connection and backward for another connection, shiftable clutches on said driving shaft for establishing said connections individually, an auxiliary shaft journaled in said frames above and driven by said driving shaft, a clutch-shifting frame having a depending yoke for engaging said clutches to establish said connections,

said clutch-shifting frame being movable lengthwise of said shafts, means for reciprocating said clutch-shifting frame directly from said auxiliary shaft, a ratchet wheel on one of said other shafts outward of one of said supporting frames, a cooperating pawl pivoted to the adjacent supporting frame, a transverse member extending between said supporting frames adjacent to said auxiliary shaft, a reciprocatory member mounted for operation on said transverse member and adapted to be actuated by said clutch-shifting frame, and means responsive to the movements of said reciprocatory member to actuate said pawl.

In testimony whereof, I hereunto subscribe my name this 12th day of July, A. D. 1921.

HENRY W. NAGEL.
